UNITED STATES PATENT OFFICE.

GEORGE W. BLAKE, OF NEW YORK, N. Y.

IMPROVED STEAM-HEATING RADIATOR.

Specification forming part of Letters Patent No. 44,156, dated September 13, 1864.

To all whom it may concern:

Be it known that I, GEORGE W. BLAKE, of the city, county, and State of New York, have invented a new and Improved Radiator for Heating Buildings or Apartments by Steam; and I do hereby declare that the following is a full, clear, and exact description thereof, which will enable others skilled in the art to make and use the same, reference being had to the accompanying drawings, forming part of this specification, in which—

Figure 1 is a central longitudinal vertical section of the radiator. Fig. 2 is a transverse vertical section of the same.

Similar letters of reference indicate like parts.

This invention consists in a radiator composed of a series of steam-tubes closed at one end and open at the other, having their open ends connected with one of the chambers of a two-chambered steam-box with which the steam-inlet pipe is connected, and having arranged within them a series of smaller tubes which are open at both ends, and connected at one end with the other chamber of the steam-box, which I term the "collection-chamber," for the purpose of permitting the escape into the latter chamber of any air that may have entered the first-mentioned tubes before the admission of steam thereinto and of the water which is formed by condensation, the said collection-chamber being provided with suitable means of egress for such air and water.

It also consists in the arrangement, within the lower tube of the first-mentioned series, of a tube for the return thereinto and through it to the first mentioned chamber of the water of condensation received in the collection-chamber, that the said water may return to the boiler by gravitation through the steam-inlet pipe.

A is the two-chambered steam-box, made with a suitable base, B, arranged in an upright position, and having an upright partition, a, by which it is divided into the two chambers b and c. The chamber b has connected at its bottom the steam-pipe d, by which steam is admitted from a boiler arranged in the basement or cellar of the building, or in any place below the radiator. The chamber c is what I term the "collection-chamber," and has the air-valve e for the escape of air from the radiator attached to its upper part. The chambers b

and c have no direct communication with each other.

C C are the steam-tubes, closed at one end and open at the other, and having their open ends screwed into tapped holes in the steam-box A, opposite to the partition a, and communicating with the chamber b. These tubes are straight and arranged horizontally one above the other, and their closed ends are supported by being inserted into holes in a post, D, which, for the sake of symmetry, is made of the same external form as the steam-box A. There is only one vertical row of these tubes in the radiator represented; but the steam-box and post may be made wider, and two or more rows of tubes used, according to the amount of heating-surface desired.

E E' are the inner and smaller tubes, open at both ends and somewhat longer than the tubes C C. These tubes are arranged near the bottoms of the tubes C C, one end of each being screwed into a tapped hole provided for its reception in the partition a, and the other being near the closed end of its respective tube C. All of these tubes E E', except that, E', in the lowest of the tubes C, are horizontal, but that one has a downward inclination toward the closed end of its respective tube C.

When steam is admitted to the chamber b of the box A, by opening the cock f in the inlet-pipe d, it fills the chamber b, and thence enters the tubes C C, driving the air from the said chamber and tubes to the closed ends of the said tubes, whence it passes through the tubes E E' into the collection-chamber c, and escapes by the valve e, which is closed, either by hand or automatically, when all the air has escaped from the radiator. As the steam is condensed in the tubes C C by their contact with the atmosphere, it escapes by the tubes E into the chamber c, and is collected in the bottom thereof, whence it runs down the inclined tube E' into the lowest tube C, and through that tube into the bottom of the chamber b, and thence by gravitation through the pipe d to the boiler. The said tube E' should be larger than the tubes E on the upper tubes C.

The advantages of this radiator consist, mainly, in its simplicity of construction and in the free escape provided for the air and water of condensation, which prevents the unpleas-

ant cracking noise so common to most other radiators.

What I claim as my invention, and desire to secure by Letters Patent, is—

1. The combination of the two chambered box A, the tubes C C, closed at one end and open at the other, and the tubes E E', open at both ends, the whole arranged substantially as herein specified.

2. The return-tube E, forming a communication between the lower part of the collect-

ing-chamber *c*, through the lower steam-tube C and the chamber *b* of the two chambered box A, to permit the return of the water of condensation from the said collecting-chamber to the boiler, through the steam-inlet pipe *d*, substantially as herein described.

GEO. W. BLAKE.
